UNITED STATES PATENT OFFICE.

JOSEPH L. WRIGHT, OF CLEVELAND, OHIO, ASSIGNOR TO WESTERN ELECTRIC COMPANY, INCORPORATED, OF NEW YORK, N. Y., A CORPORATION.

TELEPHONE-EXCHANGE SYSTEM.

Application filed August 12, 1916. Serial No. 114,516.

To all whom it may concern:

Be it known that I, JOSEPH L. WRIGHT, a citizen of the United States, residing at Cleveland, in the county of Cuyahoga and State of Ohio, have invented certain new and useful Improvements in Telephone-Exchange Systems, of which the following is a specification.

My invention relates to telephone exchange systems, and especially to systems employing operators in conjunction with automatic apparatus.

The object of my invention is to produce a system which is rapid in operation and requiring but a minimum number of acts on part of the operator at the central office to receive and establish connections.

My invention embraces such features as automatically associating a calling line with an idle operator's cord circuit or trunk, to automatically connect the operator's telephone set to the calling line and at the same time render the operator's position busy against other calls until the connection is established. In establishing connections the only duty performed by the operator is that of placing the plug associated with the trunk or cord into the jack of the called subscriber's line. The testing, ringing and automatic disconnection of the calling and called subscribers' lines is performed automatically without any attention on part of the operator.

The calling lines are automatically connected to idle trunks or cord circuits by means of what are termed tens and units relays. These relays are formed into groups and operated in order to establish connections in the manner similar to corresponding relays of the following Clement patents: 1,105,490 of July 28, 1914; 939,188 of November 2, 1909; 1,107,146 of August 11, 1914 and 1,107,152 of August 11, 1914.

In the present instance provision is made to prevent interference in case of simultaneous calls in the same or different groups of tens and units relays. Provision is also made for enabling a large number of what are termed primary trunks to be rapidly distributed among a large number of what are termed secondary trunks. These secondary trunks terminate in cord circuits located at the various operators' positions.

Other features of my invention will be pointed out in the detail description to follow.

My invention is illustrated in the accompanying drawings, wherein:

Figure 1 shows a plurality of subscribers' line equipments at the central office with a set of control relays for regulating the action of the tens and units relays.

Figure 2 shows a primary trunk with its associated tens and units relays.

Figure 3 shows the circuits and relays for controlling the tens and units relays associated with the secondary trunks.

Figure 4 shows a portion of a secondary trunk with means for controlling individual groups or sets of trunks.

Figure 5 shows a secondary trunk terminating on a cord circuit at the operator's position.

Referring to Figures 1 and 2, relay 203 represents a tens relay associated with the primary trunk, while relay 204 represents one of the units relays associated with this trunk. In practice, and as disclosed in the Clement patents mentioned, there will be a bank or group of these relays associated with each primary trunk. Each tens relay will preferably contain contacts associated with ten subscribers' lines. In case ten relays are provided then each primary trunk is capable of serving one-hundred subscribers' lines. Each trunk in this case will also be provided with ten units relays in order to form the proper cross combinations with the tens relays.

Figure 1 shows the line and cut-off relays associated with six subscribers' lines numbered 11, 12, 13, 21, 22 and 23. A set of relays numbered 1-A to 10-A, of which in the present instance only three are shown, serve to control the action of the tens relays associated with the primary trunks.

A similar group of relays numbered 1-B to 10-B of which only three are shown, serve to control the action of the units relays associated with the primary trunks. Associated with each of the relays 1-A to 10-A is a master relay such as 101 which serves to connect the units wires in a group of ten line relays so as to enable one or more relays of the group 1-B to 10-B to be operated as the case may be. As the con-

tacts associated with relays 1—A to 10—A for controlling the master relays are in series relation it, of course, follows that the operation of but one of these relays is effected. The series contacts are guarded by the portion 111 of the switch X. This switch X is a step-by-step switch provided with three sets of wipers and bank contacts designated as 111, 112 and 113. This switch is caused to step once at each call originated and also in case any abnormal condition is created.

As only one master relay such as 101 is capable of being operated at the same instant it follows that calls can be originated at the same instant from a particular group of ten lines whose connections are controlled by the operated relay 101. The operation of relay 101 serves to control the operation of the tens relay associated with the primary trunk. Each master relay as 101 controls an individual tens relay of the group. Relay 102 is operated by any relay in the group 1—A to 10—A and serves when so operated to sever the tens starting wires to prevent further operation of relays 1—A to 10—A.

The contacts of relays 1—B to 10—B which control the operation of the units relays of the primary trunks are also in series relation so that but one units relay of a group can be operated at the same time. These series contacts are guarded by means of the portion 112 of the switch X.

In case one of the series wires or contacts are broken preventing the connection from being established from the calling line to the primary trunk the switch X will automatically step thereby shifting the ground connections directly to contacts on relays of the sets 1—A to 10—A and 1—B to 10—B. During this shifting, relay 109 will be operated to restore the control relays formerly operated.

The portion 113 of the switch X controls the starting wires to the various primary trunks. When, however, connection is established the starting wire is shifted to the next trunk in the series in order to provide for uniform use of these trunks.

The starting conductor as shown in Figure 2 extends in series through the contacts of relays 206 and 202 of each primary trunk. A tap or connection is made to each primary trunk through the contacts of the portion 113 of the switch X. With this arrangement each primary trunk has an individual starting circuit extending from a particular contact on the switch X. This series arrangement is the same as that of the series contacts of the sets of relays 1—A to 10—A and 1—B to 10—B. When the switch, as shown in Figure 1, is resting on the first contact and should relays 10—A and 10—B be operated then the circuits controlled by their series contact would extend through

the contacts of all the lower relays in the series. This arrangement of wiring is made in order to guard against always starting from a certain point in the series.

Referring to Figure 3, a set of control relays similar to that of Figure 1 is shown. The operation of these relays is similar to those of Figure 1 and need not be described in detail at this point. The shifting or emergency switch Y associated with this set of relays is, however, not stepped upon the origination of each call but is only operated in case of abnormal conditions.

Referring to Figure 4, the tens and units relays 404 and 405 of the secondary trunk are operated in the same manner as are similar relays of the primary trunk and the same number of these relays will preferably be allotted to each secondary trunk.

The starting wires leading from the portion 314 of the switch Y of Figure 3 instead of leading directly to the control relays such as 403, one of which is associated with each secondary trunk are connected in multiple to contacts of a set of relays such as 401. Each relay of this set has starting conductors associated with a particular set of secondary trunks. The starting conductors are in series relation. In other words when one trunk of a group is busy a relay associated with that trunk serves to shift the starting wire to the next trunk in the series.

In case all of the trunks of a group controlled by relay 401 are busy then the switch Z will step to the next contact and thereby cause the operation of a relay as 401 associated with the next group of secondary trunks.

With the foregoing arrangement it is possible to allow the interconnection of a large number of primary trunks with an equally large number of secondary trunks.

Referring to Figure 5, the secondary trunk is shown terminating in a plug P. This plug is connected to a flexible conducting cord of the usual type. Condensers 49 and 59 are inserted in the talking conductors of the cord circuit in the usual manner. Relay 501 provided with two windings serves to supply talking current to the calling subscriber while talking current is supplied to the called subscriber through the winding of relay 504 and the winding of the retardation coil 505.

Relay 500 is automatically operated upon the origination of a call and serves to connect the operator's telephone set to the trunk while lamp 512 is also lighted at the same time thus indicating to the operator upon which trunk or cord circuit the call is connected. Relays 502 and 509 are slow acting relays, the former serving to prevent accidental disconnection of the calling subscriber's line in case he should inadvertently operate his switch hook. Relay 510 oper-

ated in conjunction with the resistance coil 129 serves to control the action of the cut-off relay of the called line. When the plug is placed in the jack J such as shown in Figure 1, relay 510 is placed in series with the cut-off relay of the line associated with the jack. When the windings of relay 510 and the cut-off relay alone are placed in series they will both operate, but when the 10 resistance coil 129 is inserted in series with the windings of these relays then relay 510 alone will remain operated and the cut-off relay will restore.

Associated with the cord circuit is a ring- 15 switch R for automatically supplying ringing current to the line of the called subscriber. Each cord circuit is provided with a four-party ringing key K of the usual locking and indicating type. Each key is 20 provided with master springs 517 which are only operated when any one of the four buttons of the set is in its fully depressed position.

The operation of the system for a local 25 call is as follows:

Subscriber No. 11 upon removing his receiver energizes the line relay associated with his line. The operation of this relay completes the circuit of relay 1-A by the 30 following path: ground, contacts of line relay, 16, contacts of relay 102, 17, winding of relay 1-A, 24, to battery B through the contacts of relay 109. The operation of relay 1-A completes the circuit of relay 102 35 and thereupon the initial energizing circuit for relay 1-A is broken. The circuit of this relay is, however, maintained locked to ground over conductor 16.

The operation of relay 1-A also 40 completes the circuit of relay 101 by the following path: ground, portion 111 of the switch X, 19, contacts of relay 1-A, 20, winding of relay 101, to battery B. The operation of this latter relay allows the circuit of relay 1-B to be completed by the following path: 45 ground, contacts of the line relay, 21, contacts of relay 101, 22, contacts of relay 103, 23, winding of relay 1-B, 24, to battery B through the contacts of relay 109. The 50 operation of relay 1-B completes the circuit of relay 103, which in operating opens the initial energizing circuit for relay 1-B which is thereafter maintained locked to ground over conductor 22.

The circuit of the control relay 200 of an 55 idle primary trunk is completed as follows: ground, contacts of relay 1-B, 40, contacts of relay 500, 41, portion 113, of the switch X, 42, contacts of relay 206, 43, winding of relay 200, to battery B. The operation of relay 200 allows the circuit of the tens' relay 60 203 to be completed by the following path: ground, contacts of relay 101, 34, contacts of relay 200, 35, winding of relay 203, to battery B. The operation of relay 200 also

allows the circuit of the units relay 204 to be completed by the following path: ground, portion 112 of the switch X, 27, contacts of relay 1-B, 28, contacts of relay 200, 29, winding of relay 204, to battery B. The 70 operation of relays 203 and 204 places relay 206 in series with the winding of the cut-off relay associated with subscriber's line No. 11 by the following path: battery B, winding of relay 206, 66, contacts of relay 204, 65, 75 contacts of relay 203, 64, winding of the cut-off relay to ground.

The operation of the cut-off relay disconnects and causes the restoration of the line relay associated with subscriber's line No. 80 11. The restoration of this relay removes ground from the locking contacts of relays 1-A and 1-B. The restoration of relay 1-A releases relay 102 and also relay 101. The restoration of relay 1-B releases relay 85 103 and also relay 200 (Figure 2).

The operation of relay 206 also serves to disconnect relay 200.

While relay 200 is energized it completes the circuit of relay 202 which disconnects 80 the starting wire 74 leading to the next trunk of the series, thus preventing any possible interference with the relays of that trunk.

The operation of relay 200 also completes the circuit of relay 201 which thereafter has its circuit completed or maintained through its locking contact to ground and to battery B through the contacts of relay 205.

The operation of relay 206 when placed 100 in series with the cut-off relay of the calling line disconnects the starting wire from relay 200 and continues it to the next trunk of the series.

The circuits of relays 203 and 204 are both 105 maintained locked to ground through the contacts of relay 201. Relay 204 has a resistance coil 31 included in its locking circuit while relay 203 has a similar coil 37 included in its locking circuit.

As soon as an idle primary trunk is selected and placed in association with the calling line in the manner just described a secondary selection is next made in order to connect the primary trunk to an idle sec- 110 ondary trunk or cord circuit.

This selection is made in the following manner: The operation of relay 206 completes the circuit of relay 300 by the following path: ground, contacts of relay 201, 115 70, contacts of relay 206, 71, winding of relay 300 to battery B. The operation of relay 300 completes the circuit of relay 1-C by the following path: ground, contacts of relay 300, 82, contacts of relay 308, 83, winding of relay 1-C to battery B through the contacts of relay 304. The operation of relay 1-C completes the circuit of relay 308. After the operation of relay 308 the circuit of relay 1-C is maintained locked to 120 125 130

ground over conductor 82. The operation of relay 1-C also completes the circuit of relay 307 by the following path: ground, portion 313 of the switch Y, 96, contacts of relay 1-C, 97, winding of relay 307 to battery B. The operation of relay 307 allows the circuit of relay 1-D to be completed by the following path: ground, contacts of relay 300, 78, contacts of relay 307, 79, contacts of relay 310, 80 winding of relay 1-D, 81, to battery B through the contacts of relay 304. The operation of relay 1-D completes the circuit of relay 310 which opens the initial energizing circuit of relay 1-D, 15 which thereafter has its circuit maintained locked to ground over conductor 79.

The operation of relay 1-D also completes the circuit of relay 401 of a group of idle secondary trunks by the following 20 path: ground, contacts of relay 1-D, 98, portion 409 of the switch Z, 99, winding of relay 401 to battery B. The operation of relay 401 allows the circuit of relay 403 associated with an idle secondary trunk to be completed by the following path: ground, contacts of relay 1-D, 104, winding of relay 309, 105, portion 314 of the switch Y, 106, contacts of relay 401, 107, contacts of relay 408, 108, contacts of relay 402, 109, 30 contacts of relay 406, 110, winding of relay 403 to battery B.

The operation of relay 403 allows the circuit of the tens relay 404 to be completed by the following path: ground, contacts of relay 307 (Figure 3), 85, contacts of relay 403, 95, winding of relay 404 to battery B. The operation of relay 403 also allows the circuit of the units relay 405 to be completed by the following path: ground, contacts of relay 309, 86, coil 87, 88, portion 312 of the switch Y, 89, contacts of relay 1-D, 90, contacts of relay 403, 91, winding of relay 405, to battery B.

The operation of relays 405 and 404 connects the primary trunk to the secondary trunk whereupon relay 402 (Figure 4) is placed in series with relay 205 by the following path: battery B, winding of relay 402, 78, 77, contacts of relay 405, 76, contacts of relay 404, 75, winding of relay 205, to ground.

Relay 405 after being energized has its circuit maintained to ground by the following path: battery B, winding of relay 405, 55 contacts of relay 405, coil 92, 93, contacts of relay 402, 112 to ground through the contacts of relay 509 (Figure 5). Relay 404 after being energized has its circuit maintained locked by the following path: battery B, winding of relay 404, contacts of relay 404, 94, winding of relay 406, 93, contacts of relay 402, 112 to ground through the contacts of relay 509. The operation of relay 402 which maintains the circuits of relays 60 405 and 404 energized in the manner just de-

scribed also shifts the starting conductor 107 to the next trunk in the series or group. Relay 409 was energized at the first operation of relay 403 and serves to sever the starting circuit leading to the next trunk in 70 the series or group to prevent interference.

The operation of relay 205 (Figure 2) removes battery from the winding of relay 201 thereby causing its restoration. The restoration of this relay removes ground 75 from the winding of relay 300 (Figure 3) which upon restoring releases relays 1-C and 1-D. The releasing of relay 1-C causes the restoration of relay 308 and also the restoration of relay 307. The restoration of relay 1-D causes the restoration of relay 310 and also relays 309, 401 and 403.

The operation of relay 402 and relay 406 completes the circuit of relay 500 (Figure 5) by the following path: ground, contacts of 85 relay 509, 112, contacts of relay 402, 113, contacts of relay 406, 114, winding of relay 500, 115, contacts of relay 510, 116 to battery B through the contacts of relay 508.

The operation of relay 500 connects the operator's telephone set directly across the tip and sleeve conductors 48 and 58 allowing her to converse with the calling subscriber. The lamp 512 has its circuit completed in 90 multiple with the winding of relay 500 thus 95 indicating to the operator that a calling line is connected to the secondary trunk or cord circuit.

The operation of relay 500 completes the circuit of relay 408 by the following path: 100 battery B, contacts of relay 508, 116, contacts of relay 510, 115, contacts of relay 500, 117, contacts of relay 408, to ground. The operation of relay 408 which is common to the particular operator's position upon 105 which a call is received, serves to shift the starting wire from all of the cord circuits associated with that position to prevent other calls being received thereon.

Relay 407 is also operated in multiple with 110 relay 408. In case there are twenty-five cords or trunks to an operator's position, relay 408 in operating will render cords 1 to 13 unselectable while relay 407 will render cords 14 to 25 unselectable.

As soon as the primary trunk is connected to the secondary trunk then battery supply is furnished to the calling subscriber through the windings of relay 501 connected to tip and sleeve conductors 48 and 58 respectively. The operation of relay 501 completes the circuit of the slow acting relay 502 but at this time no effect is produced by the operation of either of these two relays.

The operator upon learning the number desired places the plug P into the jack of the called-for line. In making this connection the operator pays no attention to the condition of the line. The insertion of the plug 125 130

places busy test relay 507 and the cut-off relay of the called line in series. As the busy test relay 507 has its winding connected to the grounded side of battery and as the 5 winding of the cut-off relay also has its winding connected to the grounded side of battery no effect is produced in case the line is idle.

The operator disregarding the fact 10 whether the line is busy or idle presses one of the ringing buttons thereby connecting the proper frequency of generator current to the cam spring 522 of the ringing switch R. The depressing of the button also closes the 15 master springs 517. The operation of these springs completes the circuit of relay 503 by the following path: battery B, contacts of relay 508, springs 517, 150, contacts of relay 502, winding of relay 503, 137, resistance 20 coil 136, 135, contacts of relay 509 to ground. The operation of relay 503 closes the tip and sleeve conductors and connects the winding of relay 510 in series with the cut-off relay of the called line by the following path: bat- 25 tery B, winding of relay 510, 130, contacts of relay 501, 131, contacts of relay 503, 126, sleeve of the plug P, jack of the called line, winding of cut-off relay to ground. The operation of relay 510 disconnects the wind- 30 ing of relay 507 and also completes the circuit of the stepping magnet 535 of the ringing switch R by the following path: ground, winding of relay 527, contacts of relay 526, 149, winding of magnet 535, 147, contacts of 35 relay 510, 146, contacts of relay 503, 145, contacts of relay 509, 144, contacts of relay 506, 138, contacts of relay 504, 139, contacts of relay 510, 116, contacts of relay 508 to battery B.

40 Relay 527 and magnet 535 operate in series. The operation of the magnet causes the switch to step while the operation of the relay completes the circuit of relay 526. This latter relay in operating breaks the 45 series circuit between relay 527 and the magnet 525 thereby causing their restoration. The restoration of relay 527 in turn causes the restoration of relay 526 which upon fully restoring again places the wind- 50 ing of relay 527 in series with the winding of magnet 535. The cooperation of the magnet and relays in this manner causes the switch to step until its circuit is interrupted. In addition to the energizing circuit of the 55 magnet 535 as just traced, its circuit is also directly completed to ground through the contacts of relay 527 when it is energized.

The switch R in stepping operates the 60 cams 518, 519, 520, 521, 522, 523, 524 and 525. The cams 519 and 521 operating open the contacts controlled by them. At the same time these contacts are broken cam 522 operates, closes its associated contacts and connects the proper generator current 65 to the tip conductor 52. The operation of

cam 523 at the same instant connects ground to the sleeve conductor 62. This ground is supplied through the back contact of relay 504. During the ringing interval cam 518 operates its associated contacts thereby connecting a suitable ring back signal to conductor 48 in series with the condenser 141.

Immediately after the ringing interval 70 and before the tip and sleeve conductors are closed by the cams 521 and 519 the cam 520 operates to connect battery to the sleeve conductor in series with the coil 511 for removing any static charge on the line. The removal of this static charge prevents any 80 possibility of the relay 504 prematurely operating.

At the first step of the ringing switch R the cam 525 closes its associated contacts and connects battery directly to the winding of the stepping magnet 535 thus insuring a complete rotation of the switch. As the magnet 535 has its circuit completed by this path the switch will continue to 90 rotate until it reaches its normal position.

The cam 524 serves to prevent the operation of relay 506 in case relay 504 should be operated by any unusual line condition or operation of the telephone by the called subscriber.

When the called subscriber answers during a non-ringing interval relay 504 is operated. The operation of this relay completes the circuit of relay 506 by the following path: battery B, contacts of relay 508, 139, contacts of relay 504, springs controlled by cam 524, winding of relay 506, 135, to ground through the contacts of relay 509. Ground is also supplied in multiple to the conductor 135 through contacts of relay 504. This latter ground connection serves to maintain relay 506 operative in case relay 509 is energized in case the calling subscriber should replace his receiver first. After relay 506 is operated its circuit is 100 maintained locked directly to battery through an associated locking contact. The operation of relay 506 opens the initial energizing circuit of the stepping magnet 535 to prevent the operation of the switch R 110 after it reaches its normal position.

When the connection was established and relay 510 operated the circuit of relay 500 was broken thereby disconnecting the operator's telephone set.

120 The restoration of relay 500 opens the circuits of relays 407 and 408 thus allowing other calls to be received upon the cord circuits associated with this particular operator's position.

At the termination of the conversation the calling subscriber replacing his receiver causes the deenergization of relay 501 and consequently the deenergization of relay 502. The restoration of the latter relay allows the 130

- circuit of relay 509 to be completed by the following path: battery B, contacts of relay 508, 116, contacts of relay 510, 139, contacts of relay 502, winding of relay 509 to ground.
- 5 The operation of relay 509 removes ground from conductor 135, but as relay 504 is operated at this time relay 503 will remain energized. The operation of relay 509, however, connects ground to the winding 10 of relay 402 by the following path: ground, contacts of relay 509, 77, 78, winding of relay 402 to battery B. As relays 402 and 205 are in series this direct ground connection serves to shunt and cause the restoration 15 of relay 205. The restoration of relay 205 removes ground from the locking contacts of relays 203 and 204 thereby causing their restoration and disconnects the line of the calling subscriber from the primary trunk.
- 20 The restoration of relays 203 and 204 breaks the series connection between relays 206 and the cut-off relay of the calling line. The restoration of relay 206 restores the primary trunk to its normal position.
- 25 The called subscriber upon replacing his receiver causes the restoration of relay 504. This relay in restoring connects battery directly to the winding of relay 503 by the following path: battery B, contacts of relay 30 508, 139, contacts of relay 504, 138, contacts of relay 506, winding of relay 503. The other terminal of this relay is also connected to battery through its locking contact, therefore, this relay will be shunted 35 and restore. The restoration of relay 503 severs the tip and sleeve conductors and allows the resistance coil 129 to be placed in series with the winding of relay 510. The insertion of this coil is between the winding 40 of relay 510 and the winding of the cut-off relay of the called line. This new series path is as follows: battery B, winding of relay 510, resistance coil 129, 128, contacts of relay 510, third conductor of the plug P, 45 thimble of the jack J, winding of the cut-off relay to ground. The resistances and adjustments of the relays are such that relay 510 will remain energized, but the cut-off relay of the called line will restore and 50 thereby allow the line relay of that line to be replaced and in readiness to be operated in case the subscriber should originate a call, although the plug remains in the jack.
- The restoration of relay 504 in addition 55 to causing the foregoing effects also momentarily connects ground to the winding of relay 510 by the following path: ground, contacts of relay 504, contacts of relay 506, normally open contacts of relay 503, normally open contacts of relay 510, coil 129, 60 130, winding of relay 510 to battery B. The effect of this momentary ground connection assists in causing the restoration of the cut-off relay of the called line as its winding 65 is also connected to ground.

As relays 509 and 504 are both deenergized at this time ground is removed from conductor 135 thereby allowing the restoration of relay 506.

The operator is made aware of the fact 70 that both subscribers have replaced their receivers, due to the lighting of the signal lamp 133 which has its circuit completed by the following path: ground, contacts of relay 509, 132, lamp 133, 134, contacts of relay 506, to battery B. The operator upon receiving the disconnect signal withdraws the plug from the jack thereby breaking the circuit of relay 510. The restoration of this relay in turn causes the restoration of relay 80 509 and the cord circuit is in condition to receive other calls.

Relay 509 in restoring also removes ground from the winding of relay 402 causing its restoration.

In case the called subscriber does not answer and the calling subscriber should replace his receiver the release of the connection is effected in the following manner: Relay 501 restoring opens the circuit of 90 relay 502. After the restoration of relay 501 and before the restoration of relay 502 ground is connected to the third conductor of the plug P by the following path: ground, contacts of relay 504, 119, back contacts of relay 506 (which is not operated under these conditions), 120, contacts of relay 501, 124, contacts of relay 502, 125, contacts of relay 503, 126, to the third conductor of the plug P. This momentary 95 ground connection serves to shunt the cut-off relay of the called line and the action of relay 509 after the complete restoration of relay 502 opens the circuit of relay 503, which upon restoring allows the resistance coil 129 to be included in series with the winding of relay 510 and the winding of the cut-off relay of the called line.

From the foregoing description it will 100 be noted that the cut-off relay of the called line is restored by the calling subscriber in case the called subscriber does not answer even though the plug remains in the jack. The same effect is produced upon the cut-off relay of the called line in case the called subscriber answers and afterward replaces his receiver.

In case the called-for line is busy when the plug is inserted in the jack, then relay 105 507 will be operated, due to battery B being supplied through the winding of a relay 510 associated with another cord circuit. The operation of relay 507 under these conditions completes the circuit of relay 508, the operation of relay 508 connects a suitable busy tone signal to the tip conductor 48 in series with the condenser 141 thus notifying the calling subscriber that the called line is busy.

The operator, of course, is not aware that 110

the called line is busy and in attempting to ring the called line by pressing the proper ringing button is unable to cause the operation of relay 503. The operation of relay 508 removes battery from the contacts 517 of the ringing key thus rendering the action of these contacts ineffective. As relay 503 is not operated it, of course, follows that relay 510 is not connected to the third conductor of 10 the plug and consequently its operation is prevented.

Relay 508, of course, is provided with a signal lamp 633, thus indicating to the operator that the called line is busy.

15 The calling subscriber upon receiving the busy tone signal replaces his receiver, causing the restoration of relays 501 and 502. The restoration of these relays completes the circuit of relay 509 by the following 20 path: battery B, contacts of relay 508, 139, contacts of relay 502, winding of relay 509 to ground. The operation of relay 509 completes the circuit of the disconnect lamp 133 and the operator observing this signal with- 25 draws the plug from the jack, allowing the restoration of relay 507, which upon restoring opens the circuit of relay 508. This latter relay in restoring opens the circuit of relay 509.

30 The selection of a group of secondary trunks is made in the following manner:

In case all the trunks in a group controlled by a relay 401 (Figure 4) which is operated are busy, it will naturally follow that relay 309 whose winding is included in series with the starting circuit will not be operated in 35 series with some trunk relay such as 403 (Figure 4). In case all of the trunks of a group are busy and relay 309 fails to operate 40 then the circuit of the stepping magnet 414 of the switch will be completed and cause the switch to step. Relay 410 is operated in multiple with the winding of relay 401 and completes the circuit of relay 411. The operation of relay 411 completes the circuit of relay 412. The operation of this latter relay allows the circuit of the stepping magnet 414 to be completed by the following 45 path: back contacts of relay 309, 100, contacts of relay 311, 101, contacts of relay 412, 102, contacts of relay 413, 103, winding of magnet 414 to battery B. The operation of the magnet completes the circuit of the vibrating relay 413 which in operating opens the 50 circuit of the magnet itself. The action set up between the magnet 414 and the relay 413 is such that the switch Z steps until relay 309 is operated in series with the winding of some relay such as 403 of an idle secondary trunk.

55 Under normal conditions relay 309 will operate and restore before the set of relays 410, 411 and 412 fully operate. It will also be noted that while relay 309 is energized 60 it completes the circuit of a slow acting re-

lay 311 which serves to open the circuit extending to the stepping magnet 414 to prevent its operation.

From the foregoing it will be noted that the switch Z will not step unless all of the 70 secondary trunks of a particular group are busy whereupon it will step and connect the next set of trunks. This operation will be kept up until a group containing an idle trunk is reached.

75 The switch X of Figure 1 is caused to step at each incoming call in the following manner: When any line relay operates it connects ground to the common conductor 25 thereby completing the circuit of relay 105 80 through the back contacts of relay 104. The operation of relay 105 completes the circuit of relay 104 and relay 104 in operating opens the circuit of relay 105. Relay 105 restoring in advance of relay 104 completes the 85 circuit of the stepping magnet 110. This stepping magnet has its circuit closed by ground supplied through the back contacts of relay 105 and the front contacts of relay 104.

90 Having thus described my invention what I desire to secure by Letters Patent is:

1. In a telephone exchange system, the combination with a plurality of primary trunks, of a plurality of secondary trunks 95 arranged in groups for interconnecting with said primary trunks, a switch common to all of the groups of secondary trunks and for determining a particular group of secondary trunks to be used, a relay individual to each group of secondary trunks, said relay controlled through said switch for determining the individual trunk to be used in said group for interconnecting with said primary trunks.

100 105 2. In a telephone exchange system, the combination of a plurality of primary trunks, of a plurality of groups of secondary trunks for interconnecting with said primary trunks, means common to all of the groups of the secondary trunks for determining the particular group of secondary trunks to be used, means individual to each group of secondary trunks and controlled through said common means for determining a particular secondary trunk in the group for interconnection with said primary trunks.

110 115 120 3. In a telephone exchange system, the combination of a plurality of primary trunks, of a plurality of groups of secondary trunks for interconnecting with said primary trunks, the individual secondary trunks of each group being in series relation, a switch common to all of the groups 125 of secondary trunks, means controlled from said primary trunks for operating said switch for determining a particular group of secondary trunks to be used, a relay individual to each group of secondary trunks,

means controlled by said switch for operating a particular one of said relays whereby the first idle secondary trunk of its group is rendered active for interconnecting with 5 said primary trunks.

4. In a telephone exchange system, the combination of a plurality of primary trunks, of a plurality of groups of secondary trunks for interconnecting with said 10 primary trunks, the individual secondary trunks of each group being in series relation, means for first automatically determining the group of secondary trunks to be used, and means for thereafter automatically 15 calling selecting an individual secondary trunk in the group for interconnecting with said primary trunks.

5. In a telephone exchange system, the combination of a plurality of primary 20 trunks, of a plurality of groups of secondary trunks for interconnecting with said primary trunks, the individual secondary trunks of each group being in series relation, a switch common to all the groups of 25 secondary trunks, contacts association with said switch, one of said contacts being allotted to each group of secondary trunks, means controlled by said primary trunks for operating said switch to determine the 30 particular group of secondary trunks to be used, means controlled over the contact of said switch allotted to the selected group for automatically selecting an idle secondary 35 trunk for interconnection with said primary trunks.

6. In a telephone exchange system, the combination of a calling and a called subscriber's line, a link circuit for interconnecting said lines, a relay associated with 40 said lines, the called line, means associated with said link circuit for energizing said relay when connection is effected between said lines, means controlled by the calling and called subscriber for momentarily shunting said 45 relay.

7. In a telephone exchange system, the combination of a calling and a called subscriber's line, a jack and a relay associated with said lines, a plug ending trunk, means 50 for automatically connecting the calling line to said trunk, means associated with said trunk for energizing the relay of the called line when the plug of the trunk is placed into the jack of the called line, means controlled over either of said lines for disabling 55 said relay while the plug remains in the jack.

8. In a telephone exchange system, the combination of a calling and a called subscriber's line, a jack associated with the called line, a cord circuit provided with a plug adapted to engage said jack, means 60 associated with said cord circuit automatically rendered operable when the plug is placed in the jack for indicating to the call- 65

ing subscriber in case the called line is busy.

9. In a telephone exchange system, the combination of a calling and called subscriber's line, a jack associated with the 70 called line, a cord circuit provided with a plug for engaging said jack, means associated with said cord circuit for automatically indicating to the calling subscriber in case the called line is busy when the plug is placed in the jack, means associated with said cord circuit and rendered active in case the called line is not busy for ringing on said line, means controlled by the called subscriber upon answering to disable said ringing, additional means controlled by said subscriber for freeing his line while the plug remains in the jack. 75

10. In a telephone exchange system, the combination of a plurality of groups of 80 trunks, the individual trunks of each group being in series relation, means common to all of said groups for automatically selecting an idle group, and means individual to each group for allowing the selection of an individual trunk. 85

11. In a telephone exchange system, the combination of a calling telephone line and a called line, a primary trunk and a secondary trunk, said primary trunk being arranged for automatic connection with said secondary trunk, said automatic selection being controlled over said calling line, a cord circuit associated with said secondary trunk, terminating in a calling plug, a jack associated with the called line, automatic means rendered operable after the plug is inserted in the jack for testing the condition of the called line, means under control of a calling line for causing the automatic disconnection of the calling line from the primary trunk and of the primary trunk from the secondary trunk, and means under control of the calling and called lines for freeing the called line from said cord 100 circuit. 105

12. In a telephone exchange system, the combination of a plurality of primary trunks, of a plurality of groups of secondary trunks for interconnecting with said primary trunks, a controlling relay individual to each of said groups of trunks, a switch common to all of said groups of trunks, and means for operating said switch in case a particular group of trunks is busy, the operation of said switch serving to energize 115 said relays in turn until a group of idle trunks is found for interconnection with said primary trunks. 120

In testimony whereof I affix my signature in the presence of two witnesses.

JOSEPH L. WRIGHT.
